BOTTLE

Gordon A. Strand, Toledo, Ohio, assignor to
Owens-Illinois, Inc., Toledo, Ohio

Filed Dec. 15, 1972, Ser. No. 315,674

Term of patent 14 years

Int. Cl. D9—01

U.S. Cl. D9—47

FIG. 1

FIG. 2

FIG. 3

FIG. 5

FIG. 4

FIG. 1 is an elevational view of a bottle showing my new design;

FIG. 2 is a top plan view thereof;

FIG. 3 is an elevational view thereof looking from the right side of FIG. 1;

FIG. 4 is an elevational view thereof looking from the left side of FIG. 1; and

FIG. 5 is a sectional view taken on line 5—5 of FIG. 3.

The side opposite that seen in FIG. 1 is a mirror image of the side shown.

I claim:

The ornamental design for a bottle, substantially as shown and described.
